Primary Examiner — Robin V Webster*Assistant Examiner* — Rachel A Voorhies(74) *Attorney, Agent, or Firm* — Sheridan Ross P.C.(57) **CLAIM**

The ornamental design for a vehicle grille, as shown and described.

DESCRIPTION

FIG. 1 is a perspective view of a vehicle grille showing one of our new designs;

FIG. 2 is a top plan view thereof;

FIG. 3 is a front elevational view thereof;

FIG. 4 is a right side elevational view thereof, the left side elevational view being mirror symmetrical;

FIG. 5 is a perspective view of the vehicle grille with an optional ornamental attachment;

FIG. 6 is a top plan view of the vehicle grille of FIG. 5;

FIG. 7 is a front elevational view of the vehicle grille of FIG. 5; and,

FIG. 8 is a right side elevational view of the vehicle grille of FIG. 5, the left side elevational view being mirror symmetrical.

The broken lines show portions of the vehicle grille which form no part of the claimed design.
